UNITED STATES PATENT OFFICE.

FREDERICK TIEMANN, OF ORDWAY, COLORADO.

WEEDING HOE.

Application filed February 3, 1923. Serial No. 616,655.

To all whom it may concern:

Be it known that I, FREDERICK TIEMANN, a citizen of the United States, residing at Ordway, in the county of Crowley and State 5 of Colorado, have invented certain new and useful Improvements in Weeding Hoes, of which the following is a specification.

My invention relates to weeding hoes, and has for the primary object thereof, the provision of such an article that may be effectively employed for removing weeds and the like from gardens in a simple and expeditious manner.

A further object of my invention, is the provision of such a weeding hoe that is of substantially simple construction, and comparatively easy of manufacture, the same being readily adapted for attachment upon one end of the wooden handle.

The nature and advantages of the invention will be better understood when the following detailed description is read in connection with the accompanying drawings, the invention residing in the construction, 25 combination, and arrangement of parts as claimed.

In the drawings forming part of this application, like numerals of reference indicate similar parts in the several views, and 30 wherein:

Figure 1— is a perspective view of the preferred embodiment of the present invention, the same being shown as secured to one end of a handle.

Figure 2— is a longitudinal cross sectional view thereof, and

Figure 3— is a view similar to Figure 1, of a slightly modified form of the invention.

Referring to the drawings in detail, the 40 hoe consists of a single member comprising a wedge shaped socket 5 adapted to be secured to one end of a wooden handle A

as at 6. Formed upon the front end of this socket and at opposite sides thereof are forwardly extending outwardly convergent 45 arms 7 connected at their front ends by an integral cross strip 8. The upper and lower edges of the form of invention shown in Figures 1 and 2, are arcuate-shaped, and are provided with knife-like cutting edges 9, 50 it being at once apparent that the tool may be inverted for employing the opposite knife edge when the other one becomes dull or otherwise impaired.

In the modification, Figure 1, only the 55 bottom edge 9' of the cross strip 8' is of arcuate form and sharpened, and in view of the above description, it is believed that the advantages and operation of a tool of this character will be readily appreciated by 60 those skilled in the art, and although I have herein shown and described the preferred embodiment of the present invention, it is nevertheless to be understood that minor 65 changes may be made therein, without departing from the spirit and scope of the invention as claimed.

Having thus described the invention, what I claim as new, and desire to secure by Letters-Patent is:

A hoe blade formed from a strip of metal having an intermediate plane portion provided with a curved cutting edge, the ends of the intermediate portion merging into converging side portions, which have edges curved toward the cutting edge of the intermediate portion, the said side portions merging into socket sections, which abut at their longitudinal edges to form a complete socket for the reception of the handle.

In testimony whereof I affix my signature.

FREDERICK TIEMANN.
